UNITED STATES PATENT OFFICE.

CHARLES T. BRENNAN, OF WATERBURY, CONNECTICUT, ASSIGNOR TO THE E. J. MANVILLE MACHINE COMPANY, OF WATERBURY, CONNECTICUT, A CORPORATION OF CONNECTICUT.

TOOL HOLDER FOR DOUBLE-STROKE SOLID-DIE HEADERS.

Application filed September 27, 1927. Serial No. 222,932.

This invention relates to the means which are employed for holding the dies in place in double stroke solid die metal heading machines, and more particularly dies which are provided for heading and extruding sections of the metal of the blanks which are acted upon in the machines.

The invention is specifically illustrated and described herein as applied to the forming of blanks for bolts and cap screws which are to be roll threaded. Manufacturers of bolts and cap screws find that roll threads are cheaper and more acceptable than cut threads in that they are more rapidly made and are stronger, and that it is easier to maintain the sizes standard.

Blanks for such articles have the sections which are to be threaded reduced in diameter as rolling the threads causes an increase of diameter. To accomplish this the bodies of the blanks are forced into dies and the sections of the metal to be subsequently threaded are extruded, that is, are slightly reduced in diameter and elongated. In practice the dies are made separable, that which reduces the diameter of the blanks is made from relatively mild carbon steel that is tough and somewhat elastic, while that surrounding the body portion of the blanks not to be threaded and against which the heads of the blanks are formed, is made of relatively high carbon steel which is much harder than the metal of the extruding die. This enables the extruding die, which wears away so that its gauge is impaired very much more rapidly than the heading die, to be removed and reground or another substituted.

The object of the present invention is to provide a simple means for holding these dies in a heading machine in such manner that while they are firmly and securely retained they may be readily removed for replacement or substitution according to their wear.

In the accompanying drawings Fig. 1 is a plan view of the front end of a heading machine frame with a die block containing dies held in place according to this invention. Fig. 2 shows a front view of the die block. Fig. 3 is a section through the front end of the machine frame, the die block, the dies in the block, and the means for removably holding the dies in place. This

view also indicates the punches which are used in machines of this character.

The die block 1 is set in a recess in the front end 2 of the machine frame and is secured therein by bolts 3, after its vertical adjustment has been determined by the screw 4. The die 5 with a perforation 6 the size of the unthreaded section of the blank, is forced into the die block from the back. The head of the blank is formed against this die and in practice it is made of relatively high carbon steel so that it will be sufficiently hard to withstand the blows of the service to which it is subjected. The die 7 with a bell mouth 8, and the perforation 9 of the diameter of the section of the blank to be threaded, is placed in die block back of the heading die. This is the extruding die which reduces the diameter the required length and somewhat elongates the blank. In practice the extruding die is made of relatively low carbon steel, that is, it is slightly softer than the heading die, in order that the transverse expansive strains to which it is subjected when it is reducing the blank will not injure the die and die block. If the heading die were as soft as the extruding die it would not withstand the blows to which it is subjected during the heading operation, and if the extruding die were as hard as the heading die must be, it would be liable to fracture the die block.

A filling die 10 inserted in a rectangular backing block 11, is placed in the die block back of the extruding die. This filling die may, in practice, be of steel having substantially the same characteristics as the heading die for it is not required to resist such heavy transverse expanding strains as is the extruding die. The rear face of the backing block is tapered and between this face and the inner face of the front end of the frame is a wedge 12. This wedge at its upper end has a flange 13 through which a screw 14 is turned against a hardened piece 15 set at the top of the frame. By means of this screw the wedge is drawn up so as to force the backing block and dies firmly into the die block.

The extruding die being of relatively soft steel and being required to resist heavy transverse expansive strains wears very much faster than the heading die and

the filling die and as it is necessary to keep it to size the extruding die must be removed at intervals and reground or another filling die substituted. With the construction illustrated when the extruding die becomes worn the die block is removed and the backing block with the filling die and the extruding die are removed from the die block. The bell mouth face of the extruding die 10 is then ground off and reamed to restore the opening to its proper size. When the parts are reassembled and the die block is again fastened to the frame the wedge, by means of its screw, is drawn up so as to 15 firmly hold and back the dies in the die block. As a result of this wedge construction the dies may be firmly and securely fastened in place regardless of the reduction of the thickness of the extruding die 20 due to repeated regrindings.

The invention claimed is:

1. The combination with the frame of a metal heading machine of a die block, means for adjusting the die block vertically, a solid 25 heading die located in a recess in the die block, a solid extruding die located in the recess in the die block back of the heading die, a backing block with an inclined rear face located in the die block back of the extruding die and a vertically adjustable wedge located between the inclined face of the backing block and the frame of the machine, whereby the heading die and extruding die may be locked in the die block by 30 the wedge regardless of variations in thickness of the extruding die or of the adjustment of the die block.

2. The combination with the frame of a metal heading machine of a die block, means 40 for adjusting the die block vertically, a solid heading die located in a recess in the die block, a solid extruding die located in the recess in the die block back of the heading die, a backing block with an inclined rear face located in the die block back of the extruding die, a vertically movable wedge located between the inclined face of the 45

backing block and the frame of the machine, and a screw for drawing the wedge into engagement with the inclined face of the backing block, whereby the heading die and extruding die may be locked in the die block by the wedge regardless of variations in thickness of the extruding die or of the adjustment of the wedge. 50

3. The combination with the frame of a metal heading machine of a die block, means for adjusting the die block vertically, a solid heading die located in a recess in the die block, a solid extruding die located in the 60 recess in the die block back of the heading die, a filling die located in the recess of the die block back of the extruding die, a backing block with an inclined rear face located in the die block back of the extruding die, a vertically movable wedge located between the inclined face of the backing block and the frame of the machine, and a screw for drawing the wedge into engagement with the inclined face of the backing block, whereby 65 the heading die and extruding die may be locked in the die block by the wedge regardless of variations in thickness of the extruding die or of the adjustment of the die block. 75

4. The combination with the frame of a metal heading machine of a die block, means for adjusting the die block vertically, a solid heading die of hard steel, located in a recess in the die block, a solid extruding die of softer steel located in the recess in the die block back of the heading die, a backing block with an inclined rear face located in the die block back of the extruding die, a wedge located between the inclined face of the backing block and the frame of the machine, and means for drawing the wedge into engagement with the inclined face of the backing block, whereby the heading die and extruding die may be locked in the die block by the wedge regardless of variations in thickness of the extruding die. 80 85 90
